[57] CLAIM

The ornamental design for a push-switch with cords as shown and described.

DESCRIPTION

FIG. 1 is a top plan view of a push-switch with cords showing my new design;

FIG. 2 is a bottom plan view thereof;

FIG. 3 is a front view thereof, the rear view being symmetrical to the front view;

FIG. 4 is a left side view thereof;

FIG. 5 is a right side view thereof; and,

FIG. 6 is a magnified cross sectional view taken along line 6-6 in FIG. 1, wherein an inner structure of the push-switch with cords is omitted.
